UNITED STATES PATENT OFFICE

LOUIS JENSEN, OF CHICAGO, ILLINOIS, ASSIGNOR TO UNITED AUTOGRAPHIC REGISTER CO., OF CHICAGO, ILLINOIS, A CORPORATION OF ILLINOIS

WEB-CONTROL MECHANISM

Application filed September 9, 1929. Serial No. 391,483.

This invention relates particularly to a machine for use in connection with continuous-form stationery, or continuous multiple-strip stationery.

5 The primary object is to equip a duplicating machine with a simple web-control device which will serve to stretch the strips across the platen.

The invention is illustrated in a preferred 10 embodiment in the accompanying drawings, in which—

Fig. 1 is a broken side elevational view of a duplicating machine embodying the invention; Fig. 2, a broken transverse vertical section taken as indicated at line 2 of Fig. 1; Fig. 3, a broken vertical longitudinal section taken as indicated at line 3 of Fig. 2, this view showing the platen and actuating means; Fig. 4, a broken plan view of that portion of the 20 machine which lies back of the portion shown in Fig. 3, the web-adjusting mechanism being shown in Fig. 4; Fig. 5, a broken vertical section taken as indicated at line 5 of Fig. 4; Fig. 6, a broken transverse section taken as 25 indicated at line 6 of Fig. 5; Fig. 7, a fragmentary sectional view taken as indicated at line 7 of Fig. 5; Fig. 8, a broken inner-perspective view, showing near the front end of its traverse a slide equipped with friction 30 pressure-plates employed for tensioning the webs during the return stroke of the slide; Fig. 9, a broken longitudinal vertical section, corresponding in a general way with the section shown in Fig. 5; Fig. 10, a perspective view illustrating the means for holding 35 the front ends of the webs; Fig. 11, a section taken as indicated at line 11—11, Fig. 10; and Fig. 12, a broken transverse vertical section taken as indicated at line 12 of Fig. 3.

40 In the construction illustrated A designates a main frame comprising a standard A' and a surmounting bed A²; B, a platen mounted in the front portion of the main frame; C, a typewriting machine which is 45 movably mounted, for line-spacing, on the rails comprising the bed A²; and D web-control mechanism mounted between the rearwardly extending arms 1 of the main frame, said arms constituting continuances of the 50 rails which comprise the bed A².

The frame A is of well-known construction. The front ends of the rails are connected by a rigidly attached cross-bar 2, which is equipped with studs or hooks 2^a adapted to engage register-perforations 2^b 55 with which the paper webs 3 are provided. The webs 3 are, in the illustration given, drawn from a roll 3^a.

The standard A' is shown as comprising a pair of foot-equipped uprights connected by 60 bolts 4 equipped with spacing-sleeves 4^a.

The platen B is movable by means of spring-held actuating mechanism 5 involving a system of levers actuated through the medium of a connecting rod 6 whose lower end 65 is joined to a pedal 7 which is pivotally mounted at 8 on a pivot carried by rigid arms 9 extending from the lower cross-rod 4.

The mechanism 5 includes a rock-shaft 10 equipped with bent arms 11 which carry a 70 clamping-member 12 which serves also as a tear-off device. The member 12 is provided with perforations 12^a adapted to fit loosely over the hooks 2^a.

By depressing the lever 7 the mechanism 5 75 is actuated against the force of the spring 13 thereof to cause the lowering of the rear end of the platen B and the lifting of the clamp-bar 12. The bed A² is equipped at the rear of the platen with a rigidly secured cross-bar 80 14 and with adjustable rigid clamps 14^a. When the platen is lowered the webs 3 are unclamped or released from the clamping action.

The typewriting machine C may be of any 85 well-known construction. It is capable of transverse movement in the operation of printing words, characters, etc.

The web-tensioning mechanism D comprises preferably an auxiliary frame 15 90 mounted between the arms 1; a slide 16 mounted on the longitudinal members of said auxiliary frame; coil springs 17 connecting the slide 16 with the frame 15 and serving normally to hold the slide in retracted position; and a chain or flexible connection 18 connected with the slide 16 and passing about a roller 19 at the front end of the frame 15, the lower end of said chain being connected with the pedal 7; and a hanger 20 in which 100

the roll 3^a is mounted, said hanger depending from hook-like brackets 21 which depend from a cross-bar 22 forming a part of the auxiliary frame 15.

5 The auxiliary frame 15 is supported on cross-bars 23 and 24 which connect the arms 1 of the bed A². The auxiliary frame is equipped at its front and rear ends with suitable hooks or projections adapted to engage the cross-bars mentioned. If desired, 10 the auxiliary frame may be lifted out of the bed of the machine.

Longitudinal members of the frame 15 are connected by transversely extending web-guides 25.

15 The slide 16 comprises a cross-plate 16^a, whose ends rest on the longitudinal members of the auxiliary frame 15; vertical blocks 16^b engage the inner vertical surfaces of the longitudinal members of the frame 15; and bottom members 16^c which engage the lower edges of said longitudinal members. The blocks 16^b are equipped with vertical pins 26.

20 Upon the cross-plate or web 16^a of the slide is supported a pile of friction plates which are shown as comprising a lower group 27 and an upper, longer group 27^a. These plates are provided near their extremities 25 with perforations 27^b which freely engage the pins 26.

The webs 3 are threaded between the guides 25 and then between the friction plates carried by the slide. The plates, by the action 35 of gravity, produce a pressure upon the webs and create sufficient friction to stretch the webs tight across the platen when the slide is retracted.

30 The rails of the frame 15 are equipped with devices 28 adapted to relieve the pressure of the plates on the webs to some extent when the slide reaches the front end of its traverse. The devices 28 are shown as comprising blocks 28^a equipped with fingers 28^b and 28^c 45 which are adapted to engage, respectively, the end portions of the lower and upper groups of friction plates. That is, when the slide nears the forward end of its traverse the plates ride upon the inclined upper edges 50 of the fingers, thus lifting the plates and lightening the pressure somewhat. If desired, the friction plates may be of graduated length and as many lifting fingers as desired may be employed. As shown, however, the 55 fingers 28^c serve to raise the upper group of plates, and fingers 28^b serve to raise the lower group, thus relieving the friction sufficiently to permit the operator to draw the paper webs forwardly when a fresh form is to be brought 60 into position over the platen.

The paper webs 3 are shown interleaved with transverse carbon strips 29 (Fig. 2) which are derived from a suitable source (not shown).

65 After a form has been printed, or filled in,

the operator depresses the pedal 7, and thus effects relative movement between the platen B and the associated clamping devices, leaving the paper webs free to be lifted from the hooks 2^a and drawn forwardly until the next 70 set of register perforations can be brought into engagement with the hooks 2^a. In the operation of unclamping the webs, as noted, the pedal 7 through the medium of the chain 18 draws the slide 16 forwardly, and causes 75 the friction plates to ride onto the plate-lifters 28. This frees the paper webs from some of the pressure of the plates, and makes it easier for the operator to draw the paper webs forwardly.

80 When the operator relieves the pressure on the pedal, the springs 17 operate to retract the slide 16. In the return movement of the slide, the friction plates exert an ironing action upon the paper webs and at the same time, by reason of the frictional engagement, draw or stretch the paper webs taut across the platen. The construction described is simple, easily operated and effective for its purpose. The paper webs are automatically tensioned 85 during the return movement of the slide.

85 When it becomes necessary to thread new forms through the machine, the friction plates are lifted off the slide, one strip is drawn across the slide, a friction plate is 90 inserted over it, another strip is drawn over first friction plate, another friction plate is placed over the second strip, and so on throughout the series.

95 The foregoing detailed description has 100 been given for clearness of understanding only, and no unnecessary limitations should be understood therefrom, but the appended claims should be construed as broadly as permissible, in view of the prior art.

105 What I regard as new, and desire to secure by Letters Patent, is:

1. In means of the character set forth: a frame equipped with a movable platen, said frame having arms extending rearwardly from the platen; an actuator serving to actuate said platen; an auxiliary frame supported between said arms; and web-tensioning means comprising a slide mounted in said auxiliary frame, and a friction plate device mounted on said slide adapted to exert retractive force on the webs in the return movement of said slide.

115 2. A machine as specified in claim 1, having a yielding device normally holding said slide in retracted position and having a connection between said actuator and slide to actuate the latter when said actuator is operated to unclamp the webs.

120 3. A machine as specified in claim 1 having a spring to retract the slide and having means to draw the slide forward, at will.

125 4. A machine as specified in claim 1, in which said friction plate device comprises a 130

pile of friction plates supported on and co-acting with said slide.

5. A machine as specified in claim 1, in which said friction plate device comprises a pile of removable gravity plates supported on and co-acting with said slide.

10. A machine as specified in claim 1 in which said friction plate device comprises a pile of friction plates supported on and co-acting with said slide, and in which means are provided for automatically relieving the pressure of said friction plates when the slide is drawn forward.

15. In means of the character set forth: a frame equipped with a platen and with co-acting web-clamping means, said frame having hooks disposed in advance of said platen, and having arms extending rearwardly from the platen; an actuator serving to produce 20 relative movement between said platen and web-clamping means to effect unclamping of the webs; and web-tensioning means comprising a spring-retracted slide mounted between the planes of said arms, and a friction plate 25 device mounted on said slide adapted to exert retractive force on the webs in the return movement of said slide.

30. A machine as specified in claim 7 having connecting means between said actuator and said slide, whereby said slide will be moved forwardly when said actuator is moved to unclamp the webs.

35. A machine as specified in claim 7, in which said slide is mounted on an auxiliary frame demountably supported between said arms and capable of being lifted vertically from its normal position.

40. A machine as specified in claim 7, in which the slide is mounted on an auxiliary frame removably supported between said arms and in which said auxiliary frame is equipped in advance of the slide with cam-devices adapted to relieve the pressure of the friction plate device when the slide is at the 45 forward end of its traverse.

LOUIS JENSEN.

DISCLAIMER

1,791,212.—*Louis Jensen, Chicago, Ill.* WEB-CONTROL MECHANISM. Patent dated February 3, 1931. Disclaimer filed November 25, 1933, by the assignee,
United Autographic Register Co.

Therefore, disclaims the following—to wit, claim 1 (except as included in claims 4, 5, and 6), claims 2 and 3, claim 7 (except as included in claim 10), claims 8 and 9.
